UNITED STATES PATENT OFFICE.

EDWARD M. WILLIAMS, OF ELYRIA, OHIO.

PISTON.

Application filed October 27, 1921. Serial No. 510,866.

The present invention relates to a piston for use in cylinders and is more particularly intended for use in the cylinders of internal combustion engines.

5 Experiment has demonstrated that when a piston of usual construction such as a cast iron piston is in actual operation in a cylinder of an internal combustion engine, the temperature at the top end or head of the piston 10 is greatest and decreases toward the inner end or skirt of the cylinder where the temperature is the lowest. This will be evident because the head of the piston is exposed directly to the heat incident to the repeated explosions of the fuel mixture. The piston being an integral body, the heat which is imparted to the head of the piston is in part transferred to the body of the piston in accordance with the laws of the conduction of 15 heat.

Such being the case, the greatest expansion of the usual type of piston occurs at the head end of the piston while the least expansion occurs at the skirt of the piston. This makes 20 it necessary to provide a variation of clearance allowance from the top to the skirt of a piston in installing the same in a cylinder and this is usually taken care of by machining a piston so that it is of slightly tapering 25 form.

The difficulties and disadvantages which are incident to the usual type of cast iron pistons and the leakage of oil around the pistons into the combustion chamber of the engine or conversely the leaking of gasoline past a piston into the crank case, and additionally, the excessive weight of cast iron 30 pistons and the disadvantage of moving the large mass of iron, are all too well known to 35 require comment.

It is the purpose of this invention to provide a piston which is so constructed that by far the greater portion of the heat which is imparted to the piston incident to its operation 40 is retained in the head portion of the piston and only a small fraction of that heat is transmitted to the central portion of the body of the piston and to the skirt of the piston. Additionally, provision is also made so that 45 heat which may be transmitted to the body of the piston is only transmitted in diminishing degree to the skirt portion of the piston.

This construction enables a piston to be

fitted much closer within the walls of a cylinder and this results directly in eliminating 55 the usual sloppy fit of a piston and on the other hand enables that the skirt portion of the piston particularly, may be fitted rather exactly and have a much closer working fit within the walls of the cylinder than can 60 possibly be attained with the types of pistons with which I am familiar.

The cylinder also provides a construction wherein the compression rings may be assembled on the piston without the necessity 65 of removing the piston from the cylinder in which it may be placed.

Reference should be had to the accompanying drawings forming a part of this specification in which Fig. 1 is a sectional elevation of a piston embodying my invention; Fig. 2 is a top plan view on reduced scale; Fig. 3 is a plan view showing the compression rings and the tension member which 70 pushes them outwardly.

Referring to the drawings, 1 indicates what may be termed the body of the piston and it is provided with the inwardly extended sleeves such as indicated at 2 for the reception of a wrist pin the same as in usual 75 practice. The upper end of the body 1 is provided with an external recess or groove which is indicated at 3, this groove being indicated for the reception of the compression ring as will be later described.

At the central portion at the top of the body portion 1 there is a boss 4 into which is threaded the member which holds the head of the piston in its attached relationship to the body portion as well be later described.

At the lower or inner end of the body portion there is also an inwardly extending groove or recess as indicated at 5, this groove or recess being for the reception of the usual oil rings.

The body portion 1 is made hollow according to usual practice.

The head of the piston is indicated at 6 and it is provided with a central retaining screw 7 which is threaded into a suitable 100 opening in the boss 4 thus serving as a retaining means for the head. There are also provided one or more auxiliary screws such as indicated at 8 which prevent relative turning between the body of the piston 1 and the head member 6. These various threaded 105

members are made to have only a fairly close fit so that when the head of the piston becomes heated and expansion takes place, the expansion of the threaded members will be possible.

The underside of the head 6 is hollowed out as indicated at 6^a so as to lighten the structure.

Means is also provided for preventing at least to a very large degree the transfer of heat between the head 6 and the body of the piston. As one means for accomplishing this general result which has been mentioned, I provide a gasket 9 which is made of any suitable composition or material which is efficient from the standpoint of the non-conduction of heat. Asbestos is a material from which such a gasket may be made. This gasket is retained between the top of the body portion 1 and the underside of the head when the head is secured on the body portion as before stated.

The skirt member of the piston is made as a separate element and secured to the body of the piston at the lower or open side thereof. In the present instance this is accomplished by providing the lower portion of the body 1 with an inwardly extending shoulder 1^a which is threaded upon its interior surface. The skirt member proper which is represented at 10 has at one end a shoulder 10^a and an upstanding neck 10^b, which on its outer surface is threaded and may be attached to the lower portion of the piston body 1 by the screw thread engagement which is suggested. This particular method of securing the two parts together is but suggestive of any desired method. The width of the shoulder 10^a is such that when assembling with the body 1 the outer surface of the body 6 is substantially in the same cylindrical plane as the outer surface of the body 1 of the piston.

It will thus be seen that the piston which has been described is made up of three parts which may be described as the head, the body portion and the skirt portion. The head is preferably made of a metal which has a low co-efficient of expansion and one which is nonwarping under the action of the high heat to which it is subjected when in use. The middle section or body portion of the piston is preferably made of a much lighter metal than the other portions and for this purpose aluminum or aluminum alloy has been found to be suitable. The lower or skirt portion of the piston is made of a material having a low co-efficient of expansion, which metal at the same time has the properties of resistant to wear.

The head member 6 is made of such a diameter with respect to a given cylinder into which it is to be fitted so that when within the cylinder and under working conditions, the expansion of the head under the temperatures to which it is subjected to in use, will

cause sufficient expansion so that the head portion will have a nice working fit within the cylinder.

The central part or body portion of the piston being made of material of low specific gravity will materially reduce the weight of the combined portions of the piston so that the total weight of the three portions may be less than the weight of the usual cast iron piston of light dimensions. The body portion is made of such diameter with respect to a given cylinder into which it is to be used, so that under expansion the body portion of the piston will have a nice working fit within the cylinder.

The skirt portion is made to have a diameter, and clearance with respect to a given cylinder so that when in use and expanded by such heat as it receives, it will have a nice working fit against the wall of the piston.

When such a piston as has been described is used, in an internal combustion engine, the first application of heat incident to the running of the engine comes upon the head of the piston and very quickly the head of the piston expands to its ultimate amount.

The conduction of heat from the head to the body portion is materially reduced due to the provision of the heat insulating means between the body portion and the head so that the body portion of the cylinder can never become as highly heated as would be the case if the body portion and head of the piston were integral. From the foregoing it will be readily deduced that the heat which the skirt portion of the piston receives, is very much less than would be the case were the piston made as an integral structure and experiment has demonstrated as a fact that the transfer of heat from the head of the piston to the skirt portion is so reduced over what would be the case in a solid piston, that the temperature which is attained by the skirt portion will never be so high as to affect the lubricating qualities of the oil used in crank case lubrication, whereas with the solid types of pistons now in use the breaking down of the lubricating oil in the crank case and destroying its lubricating properties is the usual occurrence unless a very good grade of oil be used, which is of course relatively expensive.

By making the piston in the three parts as above suggested, the head may be constructed so that it will expand in accordance with the heat which it receives and when so heated, provide a nice fit within the cylinder, also the body portion may be so made and machined that it will when expanded by the heat which it receives, have a good working fit in the cylinder, and the same is true with respect to the skirt portion. Therefore with each of these parts of the piston being particularly constructed so as to take care of the temperatures to which they are individually subjected and at the same time provide a nice fit in the

cylinder when in heated condition, insures that the piston under working conditions will at all portions of its engagement with the walls of the cylinder have a proper fit and not a loose or sloppy fit, and thereby the passage of oil beyond the piston into the combustion chamber is minimized.

Due to the fact that the skirt portion 10 may be so nicely fitted within the cylinder due to the construction of the piston as before explained, the skirt portion of the piston will always be in bearing relationship with the wall of the cylinder and so serve as a sort of a cross-head, and eliminate any other movement of the piston than a true reciprocating movement.

In the groove or recess 3 there is located the compression ring which is shown in plan view in Fig. 3 and comprises the three sections 20 which are indicated at 11, 11^a and 11^b. The ends of each of these sections are provided with notched extensions such as indicated at 12, which extensions overlap and engaging each other in the manner shown in Fig. 3. When these sections are inserted in the groove or recess 3 a spring member 13 is placed behind them, thus constantly urging the ring sections outwardly and against the wall of the cylinder. Attention is called to the fact that by the ring construction which has been shown and described, the various sections move out evenly so that the diameter of the assembled segments remains constant. This is not the case where a ring with a single split or division is used, because in such a construction the portions of the ring adjacent the split are somewhat more resilient than the portion of the ring which is 180° removed from the split.

Additionally it will be seen that by the construction of piston which has been described, the compression ring may be inserted after the piston is within the cylinder or where after the piston has been in use and it is desired to place a new compression ring in the same, the compression ring may be placed, without removing the piston from the cylinder.

This may be accomplished by removing the head of the engine and reciprocating the piston until the head of the piston is at the top of its stroke. The head 6 may then be removed, thus exposing the groove 3 and permitting the removal or placement of the segments of the compression ring.

When a new compression ring is placed in a piston it is possible to use a rather stiff spring behind the segments of the ring, and by this I mean a spring which is much stiffer than would be necessary in the actual operation of the piston. This will cause the segments of the ring to exert a rather heavy outward pressure against the inner wall of the cylinder. The head may then be placed and the engine mechanically turned over for a desired period of time, thereby wearing in the rings. After this wearing action has been permitted for a

sufficient length of time, the head of the piston may be removed and a lighter spring substituted for the heavy spring which had heretofore been used behind the compression ring. Then the head of the piston may be replaced 70 and the head of the ring assembled on the block thereof.

By the procedure which has just been outlined it is possible to give the rings a preliminary wearing in, which in the usual types 75 of piston can only be accomplished by actually wearing the rings in by use. This wearing in action makes the engine very stiff and all this may be to a large extent obviated with the type of piston herein proposed 80 in the manner which has just been described.

In the groove or recess 5 is positioned the oil ring as indicated at 14. This oil ring is constructed with segments the same as explained with respect to the compression ring 85 and the segments of the oil ring are pushed outwardly by means of a spring 15 in precisely the same manner as has before been described.

Each of the segments of the oil ring and the compression ring are retained against undue radial movement by means of pins, one of which is indicated at 16 in Fig. 1, one end of the pin being secured with a driving fit in an opening in the body member 1, while the other end of the pin extends into a slot such as indicated at 17, which slot is formed in the under side of a ring segment. The slot is slightly elliptical in shape so as to permit a limited radial movement of the ring 100 sections.

Having described my invention, I claim:

1. A piston comprising a body portion, a head portion, which head portion is separate from but secured to the body portion, 105 heat insulating means interposed between the head and body portion and a skirt portion associated with the body portion which is made separate from but attached to the lower part of the body portion, the said head portion and the said skirt portion being made of metal which has a low co-efficient of expansion as compared to that of the body portion.

2. A piston provided with a ring groove, 115 a ring in said groove, said ring comprising a plurality of similar segments with overlapping end joints, a spring behind said segments and urging them outwardly, and pins carried by the piston and engaging an edge 120 of each of said segments at the center thereof to limit the radial movement of the segments.

3. A piston having a body portion, a head which is made distinct therefrom and attached thereto and a skirt portion which is made separate from the body portion and attached to the lower end of the body portion, said head and skirt being made of metal having a low co-efficient of expansion and said body portion being made of a metal 130

which is materially lighter than the metal of the head and skirt.

4. A piston having a hollow body portion provided with means for attachment to a connecting rod, a head separate from said body portion and attached thereto, heat insulating means between said head and body portion, and a skirt separate from the body portion and attached to the lower end there-

of, said head and skirt being made of metal having a low co-efficient of expansion, and said body portion being made of a metal which is materially lighter than the metal of the head and skirt.

In testimony whereof, I hereunto affix my signature.

EDWARD M. WILLIAMS.
